UNITED STATES PATENT OFFICE.

ALBERT E. THORNLEY, OF PAWTUCKET, RHODE ISLAND.

TENNIS RACKET.

Application filed December 24, 1924. Serial No. 757,861.

To all whom it may concern:

Be it known that I, ALBERT E. THORNLEY, a citizen of the United States, residing at Pawtucket, in the county of Providence and 5 State of Rhode Island, have invented new and useful Improvements in Tennis Rackets, of which the following is a specification.

This invention relates to certain new and useful improvements in tennis rackets, and 10 the primary object thereof is to provide improved means for strengthening the throat of the racket, which as is well known, is subjected to the greatest strain and stress.

A further object of the invention is to 15 provide means of the character set forth which is of simple and economical form.

A still further object of the invention is to provide throat strengthening means in the securement of which drilling is involved, 20 so as to conform to the necessary and usual drilling operations incident to stringing of the racket.

The invention also aims to provide 25 strengthening means which are related or combined so as to mutually coact or cooperate in resisting the strains and stresses to which the throat is subjected in the use of the wood.

In the drawings:

30 Figure 1 is a fragmentary side elevation, partly broken away and in section.

Figure 2 is a section on line 2—2 of Fig. 1 and

35 Figure 3 is a section on line 3—3 of Fig. 1.

In proceeding in accordance with the present invention, a series of relatively large 40 diametered dowel pins 1, 2 and 3 are employed. The dowel pin 3 extends transversely across the handle and the throat T, at the inner end of the handle, while the dowel pins 1 and 2 extend in converging relation across the end portions of the top of the throat. The three pins thus present a substantially triangular formation. The

45 pins 1 and 2 it will be noted extend across the relatively sharply curved parts F of the sides of the bow and the end portions of the throat while the pin 3 is common to each of the end portions of the bow that are disposed on opposite sides of the throat and 50 form the handle of the racket in conjunction therewith.

The dowel pins are received and glued in openings drilled therefor in the racket

frame, and since stringing of the racket necessitates drilling it will be apparent that the drilling of the holes to receive the three dowel pins 1, 2 and 3 can be performed as a part of the usual drilling operation. Thus the invention can be carried out in an 60 economical manner, both as concerns time, labor and cost of material, since the three dowel pins may be formed of ordinary dowelling and can be easily and quickly glued in position. 65

The invention is particularly of advantage in adding strength to the racket throat so as to compensate for the difference in the grain of the wood, which as is well known varies considerably. The pin 3 it will be 70 thus seen extends across the racket frame at the juncture of the handle proper and the base of the throat, while the pins 1 and 2 reinforce not only the sides of the throat but also the curved parts of the bow that 75 flank the throat.

Having thus described my invention, what I claim as new and desire to secure by Letters Patent is:—

1. In a tennis racket, a frame having a 80 throat and a bow the ends of which are secured on opposite sides of the throat, a dowel pin extending transversely across the throat at the inner end of the handle, and a pair of spaced dowel pins extending across 85 the parts of the bow flanking the throat and the adjacent parts of the latter and converging toward the bow.

2. A tennis racket having a series of 90 dowel pins, secured in the throat thereof, and in substantially triangular relation.

3. A tennis racket having a dowel pin extending transversely across the throat at its juncture with the handle proper and having other dowel pins extending across the 95 bow sides that flank the throat and across the inner end of the latter.

4. A tennis racket, a series of dowel pins one of which extends across the throat and others of which extend across the parts of 100 the bow adjacent to the throat.

In testimony whereof, I have signed my name to this specification in the presence of two subscribing witnesses.

ALBERT E. THORNLEY.
